UNITED STATES PATENT OFFICE.

ABRAHAM W. MEES, OF MASON, WEST VIRGINIA.

PUZZLE.

1,251,400.

Specification of Letters Patent. Patented Dec. 25, 1917.

Application filed February 8, 1916. Serial No. 76,941.

To all whom it may concern:

Be it known that I, ABRAHAM W. MEES, a citizen of the United States, residing at Mason, in the county of Mason and State 5 of West Virginia, have invented certain new and useful Improvements in Puzzles; and I do hereby declare the following to be a full, clear, and exact description of the invention, such as will enable others skilled in the 10 art to which it appertains to make and use the same.

This invention relates to puzzles the principal object of the invention being to provide a puzzle of comparatively simple construction which may be manufactured at 15 low cost, and which will be capable of many phases or combinations, some of which may be quite easy of solution, and others very difficult.

20 The foregoing and other objects may be attained by means of the construction illustrated in the accompanying drawing, in which,

Figure 1 is a top plan view of a puzzle 25 made in accordance with this invention, and showing eight blocks or cubes arranged in a box with like characters shown upon the upper side thereof.

Fig. 2 is a plan view showing one phase 30 of the puzzle during the last step of the process of solving the same from the arrangement shown in Fig. 1.

Fig. 3 is a top plan view of the box for containing the blocks.

35 Fig. 4 is a perspective view of one of the blocks.

Fig. 5 is a perspective view of the same block from a different angle, and

Fig. 6 is a sectional view taken through 40 the box for containing the blocks.

Referring to the drawing the numeral 1 designates the blocks or cubes provided with beveled edges or corners 2. Each of the blocks has upon its faces a representation 45 of a diamond, a heart, a spade, a club, an ordinal or figure and a letter of the alphabet. There are eight blocks in all and they are placed within a box 3 of rectangular form and of slightly greater area than the

50 sum total of the blocks. The box 3 is made of tin or suitable metal having punched from the lower side thereof a number of perforations forming projecting burs 5 upon the upper surface of bottom 4 of said box.

55 The blocks or cubes 1 are placed within

the box 3 with the central space left vacant and in order to solve one of the many phases of the combinations of the puzzle, all the diamond sides of the blocks may be placed upward as shown in Fig. 1 and the object 60 will be to move the blocks by turning them on their edges without lifting the blocks from the bottom of the box or without sliding the blocks so that all the clubs may be exposed at the top of the blocks, and in Fig. 65 2 is shown the last block ready to be rolled over to expose all clubs at the top with the central space vacant shown in Fig. 1.

The burs 5 are for the purpose of engaging the blocks during the movements of 70 75 rolling them over upon their beveled edges and for preventing the blocks from sliding.

It will be obvious that there are many combinations which can be worked with this puzzle, and the one already described is perhaps one of the simpler ones.

Various changes may be made in the details of construction, arrangement and use of different characters without departing from the spirit and scope of the invention as 80 defined in the claims.

What is claimed is:

1. A puzzle comprising a square box and eight blocks or cubes adapted to fill the box leaving one space vacant and having on the 85 different faces thereof different characters, each block being a duplicate of the other blocks, said blocks having beveled edges and said box having a roughened bottom.

2. A puzzle comprising a plurality of 90 blocks or cubes each having different characters upon the faces thereof, said blocks being arranged in a square box leaving one space unoccupied, the bottom of said box being provided with a frictional surface so 95 that the blocks will be engaged for turning without sliding.

3. A puzzle comprising a rectangular metal box having the bottom provided with perforations having upwardly projecting 100 burs, and a plurality of blocks mounted in the box and provided with beveled edges, said blocks adapted to be rolled or turned over in the box without sliding.

In testimony whereof I affix my signature 105 in presence of two witnesses.

ABRAHAM W. MEES.
